UNITED STATES PATENT OFFICE.

WILLIAM J. KAYSER, OF MILWAUKEE, WISCONSIN.

CHIMNEY CAP AND VENTILATOR.

SPECIFICATION forming part of Letters Patent No. 299,227, dated May 27, 1884.

Application filed January 14, 1884. (No model.)

To all whom it may concern:

Be it known that I, WILLIAM J. KAYSER, of Milwaukee, in the county of Milwaukee, and in the State of Wisconsin, have invented 5 certain new and useful Improvements in Chimney Caps and Ventilators; and I do hereby declare that the following is a full, clear, and exact description thereof.

My invention relates to improvements in 10 caps and ventilators for chimneys, and will be fully described hereinafter.

In the drawings, Figure 1 is a vertical sectional view of my improved cap and ventilator. Fig. 2 is a perspective view of the same; 15 and Fig. 3 is a vertical sectional view on the line $\alpha\alpha$ of Fig. 1.

A is the pipe, to the top of which the cap is attached, and which may be secured on top of the chimney B in any suitable manner. Fastened on, opposite each other, to the pipe A 20 are the sheet-metal cone-frustums C C, to form the ventilator and cap. These cone-frustums C are provided with a flange, a, projecting around their base. They are fixed to the pipe 25 so that the top of this last will be somewhat higher than the upper edge of the cone-frustum top c, and a part of the flange a, as well as of the base of the cone-frustums, is cut out or shaped so that when the two are fastened in 30 place around the pipe A this latter is encircled by the cone-frustums, except at the center, where a space is left open between the same. The mode of fastening is of course immaterial, as, whether bolts, rivets, or simply solder 35 be used, my invention remains the same. The upper half of the space left between the opposite cone-frustums is covered over by a sheet-metal band, D, the ends of which are suitably fastened to the flange a on a line passing horizontally through the center of said cone-frustums. From the point at which this band D is attached to the flange a it is given an outward bend, at e, so as to raise it somewhat 45 above the rim of the cone-frustums to leave a sufficient opening for the smoke, soot, and foul gases coming out of the pipe A. The band D is, moreover, made wider than the space left between the cone-frustums, and its edges (which may be inclined or bent 50 upward, as in Fig. 1,) overlap the outer face of the flange a, so as to fully protect the

top opening and the pipe A against rain or snow as well as against return-drafts. The part of the space left between the cone-frustums that lies below the points of attachment 55 of the band D is divided into two about equal parts by the sheet-metal strips f f, the lower ends of which are fastened to the flange a, either by rivets or solder. These strips are made to project up toward the center of the 60 cone-frustums and inside a slot, g, made in the pipe A, opposite the open space between the same. The slot g is made of about the same width as that of the open space between the cone-frustums, and is extended above and below the point which the strips intersect as they project through said slot inside the pipe A, 65 and to which they are suitably fastened. The lower part of the metal cut out of the pipe A to form the slot or side openings, g, is bent inside the pipe, as shown at h, on a line parallel with the strips f, thus forming with the upper part of said strips, projecting inside the pipe A, a continuation of the sluice or air-vent produced in the lower part of the open space 70 below the cap-band D. The strips f f serve to direct the draft upward to the top of the pipe A and through the slot g, and to prevent its scattering around said pipe. The top of the cone-frustums C is left open, as shown at 75 80 c, and through this opening and the partitioned space left open between the same drafts will be forced up toward the top of the pipe A, whereby the smoke, steam, vapor, foul gases, and soot will be effectually induced out of the 85 chimney B, whatever may be the direction of the wind.

Having thus described my invention, what I claim as new, and desire to secure by Letters Patent, is—

1. In a chimney cap and ventilator, the combination of two open cone-frustums attached opposite each other close to the top of the chimney-pipe, and adapted to direct forced drafts upward toward the top of said pipe, 95 with a sheet-metal band fastened to the base of said opposing cones and adapted to cover the upper half of the open space left between them, to protect the chimney-pipe against return-drafts and rain or snow, substantially as 100 set forth.

2. In a chimney cap and ventilator, the

cone-frustums C C, having a flange, *a*, around their open base, and top openings, *c*, in combination with the protecting band D and the chimney-pipe A, substantially as shown and described, and for the purpose set forth.

3. In a chimney cap and ventilator, the cone-frustums C C, having the dividing-strips *ff*, in combination with the pipe A, having the band D and the slots *g g* and strips *h h*, substantially as shown and described, and for the purpose set forth.

4. In a chimney cap and ventilator, a pipe having side openings and cone-frustums secured opposite each other, and having open tops located alternately with and midway between the openings in the pipe, to create a blast-draft straight out through the top of the pipe, substantially as set forth.

5. A combined ventilator and chimney cap consisting of a pipe having side openings and top opening protected by a weather-band, and open cone-frustums, as described, whereby a straight forced upward draft is insured, irrespective of the direction of the wind, substantially as set forth.

In testimony that I claim the foregoing I have hereunto set my hand, at Milwaukee, in the county of Milwaukee and State of Wisconsin, in the presence of two witnesses.

WILLIAM J. KAYSER.
